UNITED STATES PATENT OFFICE

Patent No. 2,537,701

ELASTIC GOLF BALL POCKET

William T. Previdi, Allendale, N. J.

Application March 14, 1947, Serial No. 734,763

5 Claims.

(Cl. 2—250)

1 This invention relates to garments for golfers

and more particularly to a pocket construction for carrying one or more golf balls.

It is an object of the present invention to provide a pocket on a garment for a golfer which is particularly adapted for carrying golf balls and which is formed of elastic material which can be stretched in either one or two directions. This pocket, wherein there will be provided a cover of waterproof material adapted to be extended over the elastic material to keep the same clean and free from dampness and to particularly house the same when the pocket is not in use, will resiliently retain the golf ball when it is disposed within the pocket.

Other objects of the present invention are to provide a golf ball pocket for garments which is of simple construction, inexpensive to form into the garment and efficient in operation.

According to the invention, the golfer's blouse is formed with a band at the lower end, on which is disposed the pocket of elastic material adapted to receive at one end of the same a golf ball. This pocket will expand to conveniently and positively retain the golf ball against movement out of the pocket opening. Also fixed to the band is a cover of flexible material hinged at the top part of the band and adapted to extend down over the pocket of resilient material to prevent the resilient material from getting wet. The cover is adapted to allow the pocket to project from beneath it and when the pocket for the golf balls is not in use, the cover is adapted to extend down over the pocket opening flatly to cover up the golf ball pocket. Snap fasteners are used for securing the lower edge of the band to the blouse. This cover flap may have elastic material in it so that it can be stretchedly extended over the golf ball pocket when the pocket is filled with golf balls and still be snapped to the blouse at the lower edge in the aforesaid manner. Instead of snap fasteners, a "zipper" arrangement may be used to secure the lower edge of flap to the blouse when the cover flap is made of elastic material.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a rear perspective view of a golfer's

garment having a band at the bottom end, on which the golf ball pocket of the present invention is disposed.

Fig. 2 is an enlarged fragmentary view looking in elevation upon the cover flap adapted to be brought down over the golf ball pocket.

Fig. 3 is a cross sectional view taken on line 3—3 of Fig. 2.

Fig. 4 is a fragmentary view similar to Fig. 2 except that the flap has been raised and golf balls have been inserted in the resilient pocket.

Fig. 5 is a cross sectional view taken on line 5—5 of Fig. 4.

Fig. 6 is a detail cross sectional view taken 15 through the opening rim of the resilient pocket on line 6—6 of Fig. 4.

Fig. 7 is a perspective view of a modified form 20 of flap which is comprised of resilient or elastic material thus permitting the flap to be stretched over the golf balls within the now elastic pocket.

Fig. 8 is a cross sectional view taken on line 8—8 of Fig. 7.

Fig. 9 is a perspective view of a modified form 25 of the invention having a resilient material comprising the flap and a "zipper" arrangement for securing the cover flap in its closed position.

Fig. 10 is a fragmentary front elevational view 30 of a pocket construction having a slightly different arrangement of the openings forming the pocket of the elastic material under the flap.

Fig. 11 is a view similar to Fig. 10 but where the flap has been raised to expose the elastic pocket container holding golf balls, which have been inserted from top openings, disposed therein:

35 Referring now particularly to Figs. 1 to 6, a golfer 15 is provided with a garment or jacket 16 having a bottom wide band 17. On this wide band, there is connected an elastic pocket piece 18 which is open at one end, as indicated at 19, 40 to receive golf balls 21. This pocket 18 is formed of elastic material and will expand as the golf balls are inserted into the same. This elastic piece extends in the same direction as the band and has at its open end a reinforcing piece 22

(Fig. 6), to prevent the outward movement of the ball once it has been inserted within the pocket. This insert reinforcing piece 22 may be slightly resilient to permit the insertion of the ball but will then spring closed sufficiently to retain the ball within the pocket unless considerable force is applied behind the ball to take it out of the pocket.

In order to cover the elastic pocket piece 18 at times when the pocket is not in use, there is

provided a flap 24 which is sewed at its upper edge to the band and which is adapted to extend down over the band to lie flush over the pocket and over the band. This flap additionally has fastener elements 25 adapted to attach with complementary fastener elements 26 on the band 17. The flap is shown in the closed position in Fig. 2 and in the raised or open position in Fig. 4.

Referring now to Figs. 7 and 8, the flap is indicated at 27 and includes an elastic strip 28 connected at its upper edge to the top of the band so as to permit the flap to be stretched downwardly and whereby the flap 27 can be connected by its fasteners 25 over the pocket even though the golf balls have been inserted therein. This arrangement is such that the flap will be contracted to lie flat over the golfer's pocket when the golf balls have been removed therefrom.

Referring now to Fig. 9, there is shown the use of a "zipper" arrangement 31 including a slide 32 adapted to be connected between a lower edge of flap 33 to a strip 34 having one of the "zipper" parts. This flap can be extended over the pocket even though it is filled. This flap 33 is provided with an elastic top strip 35, the same as provided with the form of the invention shown in Fig. 7.

Referring now to Figs. 10 and 11, it will be noted that the jacket 16 is similarly formed with a band 17 but wherein the elastic material is sewed upon the band so as to provide openings 38 through which golf balls 21 can be extended. Instead of providing a side pocket with an opening at one end or side, there are provided two pockets with openings extending from the tops of the same. Thus there is provided a separate pocket for each golf ball. The material, as indicated at 39, of which the pockets are made, are of the similar elastic material which can be stretched in two directions. Flap 24 can be extended downwardly over the pockets when the pockets are not in use, in the same manner as described above, also the pocket can have an elastic strip extended across, as described above, in connection with the other forms of the invention, so that it can be extended while the pockets are filled with golf balls.

It should now be apparent that there has been provided a golf ball pocket which is open only at one end to receive the golf balls and wherein the golf balls in order to be extended into the pocket, are moved laterally in the direction of the band and under a reinforced opening portion of the pocket. It should also be apparent that there has been provided a cover flap, which can be extended over the pocket when the pocket is not in use, and also when it is in use, such arrangement made possible by the provision of an elastic piece in the cover flap.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A pocket construction for garments com-

prising a pocket formed of resilient material secured along its top and bottom edges and at one end thereof to the garment and having an opening extending in a vertical plane at the other end of the pocket and through which golf balls or like articles can be dispensed, said pocket opening having a reinforced piece within the pocket material adapted to expand only slightly to permit the insertion of a golf ball and adapted to lock the golf ball within the pocket.

2. In combination with a garment having a non-elastic waist band, a pocket comprising a strip of resilient material secured unstretched to said band along three sides and being free of said band at its fourth side and cooperating with said band to form a pocket there-between, said elastic material being arranged to contract closely about articles inserted into said pocket, and a reenforcing piece mounted along the free edge of said strip of resilient material.

3. In combination with a garment having a non-elastic waist band, a pocket comprising a strip of resilient material secured unstretched to said band along three sides and being free of said band at its fourth side and cooperating with said band to form a pocket there-between, said elastic material being arranged to contract closely about articles inserted into said pocket, and a reenforcing piece mounted along the free edge of said strip of resilient material, said fourth free side being along a vertical edge of said strip of resilient material.

4. In combination with a garment having a non-elastic waist band, a pocket comprising a strip of resilient material secured unstretched to said band along three sides and being free of said band at its fourth side and cooperating with said band to form a pocket there-between, said elastic material being arranged to contract closely about articles inserted into said pocket, and a reenforcing piece mounted along the free edge of said strip of resilient material, said fourth free side being along the top edge of said strip of resilient material.

5. In combination with a garment having a non-elastic waist band, a pocket comprising a strip of resilient material secured unstretched to said band along three sides and being free of said band at its fourth side and cooperating with said band to form a pocket there-between, said elastic material being arranged to contract closely about articles inserted into said pocket, and a reenforcing piece mounted along the free edge of said strip of resilient material, said reenforcing piece being slightly flexible enabling said free side to be expanded to engage articles into said pocket.
